FIG. 1

FIG. 2

FIG. 3

FIG. 4

FIG. 5

FIG. 6

FIG. 7

FIG. 8

FIG. 1 is a perspective view of a rasp wheel looking from one end showing my new design.

FIG. 2 is a similar view as viewed from an opposite end of the wheel.

FIGS. 3 and 4 are similar to FIGS. 1 and 2, but showing a modified form of the invention.

FIGS. 5 and 6 are views also similar to FIGS. 1 and 2, but showing an additional modified form of the invention.

FIGS. 7 and 8 are further views similar to FIGS. 1 and 2, but showing a still further modified form of the invention.

I claim:

The ornamental design for rasp wheels, substantially as shown in the drawings.
